FENDER SIGNAL ARROW AND PARKING
LAMPJohn Ralph Haines, Vincentown, N. J., assignor
to Arrow Safety Device Company, Inc., Mount
Holly, N. J., a corporation of New JerseyApplication March 11, 1932, Serial No. 598,247
Renewed March 27, 1936

3 Claims. (Cl. 177—329)

The present invention relates to an improved fender signal arrow and parking lamp housing one adapted for each fender of a motor vehicle and the purpose of the invention is to provide an article of manufacture of this kind, which will give direction of the vehicle from the front or from the side, said casing including two compartments one for a parking light bulb and the other for a direction indicating bulb, the side and front 5 wall of the casing having arrows for indicating a turn, in the present instance the arrows indicate a left turn.

Another purpose is to provide, in a device of this kind a bullet-shaped casing provided with an elongated footed pedestal for mounting the casing on the fender, there being means passing through the wall of the casing and through the pedestal for fastening the parts together and on the fender.

Another purpose is to provide in a device of 20 this kind, an improved one piece partition, which divides the interior of the casing, at a point above the arrow openings into two compartments, the lower compartment for the bulb for reflecting the light rays through the arrows openings, an upper compartment for the reception of a bulb for reflecting light rays through a parking light opening, the bulb for the arrow openings being extinguished when the bulb for the parking light opening is lighted.

Another purpose is to provide a one piece partition comprising a horizontal portion at the front of the lamp casing merging into a vertical part to divide off an upper compartment for the 35 reception of a bulb with a transparent covered opening in front as a parking lamp, said vertical portion merging into an inclined portion and a second vertical portion, dividing the interior of the casing into a second compartment containing a lamp bulb for illumination through transparent covered direction arrows, said second vertical portion merging into an extension in conformity to the interior rear curvature of the casing, to receive the securing means between the 40 casing and the elongated footed pedestal, to assist in holding the partition in place, it being observed that the lamp bulbs are mounted in sockets carried by both vertical portions of the one piece partition.

It is to be understood that the particulars herein given are in no way limitative, and that while still keeping within the scope of the invention, any desired modification of details and proportions may be made in the construction of the 50 appliance according to circumstances.

The invention comprises further features and combination of parts to be hereinafter set forth, shown in the drawing and claimed.

In the drawing:—

Figure 1 is a view in perspective of the improved fender signal arrow and parking housing constructed in accordance with the invention.

Figure 2 is a sectional view on line 2—2 of Figure 1.

Figure 3 is a sectional view on line 3—3 of Figure 2.

Figure 4 is a detail view of the partition.

Referring to the drawing 1 identifies an elongated footed pedestal, the under-curvature of the foot being such as will conform to the curvature 15 of a fender. This footed pedestal merges into a contracted neck 2, which in turn swells into a supporting base 3, for the support of the fender signal arrow and parking lamp casing.

This casing 4 is bullet-shaped, and the curvature of its wall conforms to the curvature of the supporting base 3 of the pedestal. An opening 5 is formed through the pedestal and it registers with an opening 5a in the wall of the casing 4, for the reception of suitable leads or 25 wires from the bulbs 6. Suitable screws 7 pass through the wall of the casing and through the pedestal and also through the fender 8 and receive nuts 9 on their lower ends, thereby holding the parts together and mounted upon the 30 fender. The casing receives a flanged cover 10, which is provided with an arrow opening 11, which in the present instance indicates a left turn. The cover is secured in position by means of screws 12 and is provided with a second opening 13 of an elongated curved formation above the arrow, for the reflection of light rays for 35 parking purposes. One side of the casing is formed with an arrow opening similar to that in the cover and is designed to likewise indicate a left turn. This arrow opening 14 in the side of the casing is for the purpose of permitting the direction to be indicated from the side while the arrow in the cover indicates the direction from the front.

Arranged in the interior of the casing is a partition 15, which divides the interior of the casing into two compartments 16 and 17, the former being incident to the elongated curved opening in the cover, the latter being incident to the 50 two arrow openings. This partition 15 has a socket 18 for a bulb 6 for illuminating the compartment 16.

The single piece partition comprises a horizontal transverse portion 19, which at the rear 55

merges into a vertical part 20. These parts 19 and 20 are in conformity to the circular contour of the lamp casing. The vertical part 20 merges into an inclined portion 21, which in turn merges 5 into a second vertical portion 22, which has a socket 23 for the lamp bulb 6. As will be noted the two lamp bulbs 6 and 6a are carried by the first and second vertical portions of the partition, while the wires or leads 24 and 25 are 10 connected to suitable contacts 26 on the rear faces of the first and second vertical portions. These wires or leads pass through the opening 5 formed through the pedestal and are adapted to lie under the surface of the fender, in any 15 conventional way. The forward opposite corners of the transverse horizontal portion 19 of the partition are provided with corner pieces or brackets 26, certain portions 27 of which are electrically welded to the interior surface of the 20 casing, while the portions 28 receive the screws 12, which pass through the cover 10 for holding the cover in place.

The invention having been set forth, what is claimed is:

25. 1. A fender lamp, comprising a lamp housing, a pedestal on a fender for the housing, a one piece partition within the housing, said partition comprising a vertical portion having a curved extension at its lower part engaged with 30 the rear and bottom portion of the interior of the housing, said vertical portion having an upwardly inclined part extending into a second downwardly extending vertical portion, said second downwardly extending vertical portion extending 35 into a horizontal wall provided with corner supports secured to the wall of the housing, said partition dividing the interior of the housing into three compartments, two of which contain light bulbs supported on the partition, and 40 means passing through the extension, the rear bottom wall of the housing and through the pedestal and the fender for securing said members together.

2. In a turn signal device for vehicles, a cas-

ing having a front circular cover and a lens between the cover and the circular edge of the casing at the front, a plate having a portion engaging a wall of the casing and another portion extending inwardly from said wall and conforming to the shape of the casing engaging the latter and forming a rattle preventing support for a lamp socket, the inwardly extending portion of the plate having a lamp socket, said plate having a vertical part extending from said first named wall engaging portion and provided with a second lamp socket, said plate also including a horizontal broad portion connected to the lower part of the vertical part and conforming to the sides of the casing, the forward corners of this horizontal broad portion of the plate having lugs at right angles to each other, and securing means passing through the lugs at two points, one of said securing means fastening the lugs to the front cover and the lens, the other securing means connecting the lugs to the opposite sides of the casing, thereby providing a rigid structure.

3. In a turn signal device for vehicles, a casing, a plate within the casing, having a portion engaging a wall of the casing and another portion extending inwardly from said wall and conforming circumferentially to the shape of the casing engaging the latter, said other portion constituting a rattle-preventing support for a lamp socket, a lamp socket supported by said inwardly extending portion, a casing support having means engaging said wall of the casing at the exterior thereof in substantial alignment with the casing and a wall engaging portion of said plate, securing means fastened through said support and casing and connecting the same together, and also supporting said wall engaging portion, means on the other end of said support for attaching same to a vehicle, said support and casing being provided with aligned openings for the passage of conductors for the lamp socket.

JOHN RALPH HAINES.
